UNITED STATES PATENT OFFICE

PHILIP R. THOMAS, OF ALDWYCH, LONDON, ENGLAND, ASSIGNOR TO WESTERN ELECTRIC COMPANY, INCORPORATED, OF NEW YORK, N. Y., A CORPORATION OF NEW YORK

TRANSMISSION CONTROL CIRCUIT

Application filed October 30, 1931, Serial No. 571,947, and in Great Britain December 23, 1930.

This invention relates to electrical communication systems and more particularly to those systems in which both telegraph and telephone messages are transmitted over the same cable, the direction of transmission of 5 telegraph being under control of the speech.

In such a system it is desirable to arrange the switching means for conditioning the line so that at times of commencement or change- 10 over of direction of transmission of telegraph the signals are not clipped or abbreviated or even lost completely due to the time taken to perform the switching operations.

In accordance with the present invention there is provided in a cable system comprising 15 speech and telegraph circuits where the direction of transmission of telegraph is under the control of the speech, means to delay the application of telegraph signals to any part of 20 the system until such part is in a condition for transmission.

By way of illustration, one embodiment of 25 the invention will be described with reference to the accompanying drawing which illustrates one terminal of a cable system.

Referring to the drawing it will be seen to 30 represent one terminal of a cable in a receiving condition.

The cable terminates in a four-wire circuit 35 in the usual manner comprising telephone branch L_1 , L_2 , telegraph branch TL_1 , TL_2 and the filters F_1 and F_2 for separating telephone and telegraph signals. In the tele- 40 graph branch there is shown the usual tele- graph transmitting and telegraph receiving 45 amplifiers designated TA_1 and TA_2 , respectively and a telegraph transmitter TT . In the telephone branch are the usual amplifiers A_1 and A_2 and the additional apparatus des- 50 ignated D and AD_2 with switches S_1 , S_2 and S_3 operated by the latter. D is a delay net- 55 work designed to delay the speech in L_1 for a period long enough to enable switches S_1 , S_2 and S_3 to operate in response to operation of 60 the apparatus AD_2 , which may be a vacuum tube amplifier-detector circuit such as is well known in the art, under control of the speech picked off from L_1 in front of the delay net- 65 work D , before the speech arrives at the 70 switching point in L_1 . Sufficient apparatus

to render clear the working of the invention only has been shown and it will be appreciated by those skilled in the art that other well known apparatus will be required to complete the terminal equipment.

Assume now that speech arrives on the line 55 L_1 . It will be amplified by amplifier A_1 , the output of which will divide between delay network D and amplifier detector AD_2 . The main portion of the speech passes through 60 the delay network where its transit time is appreciable, the network being designed according to known principles to produce a delay greater than the time required by the switches S_1 , S_2 and S_3 to operate. Some of 65 the speech is diverted through amplifier detector AD_2 , the output of which operates the three switches. S_1 puts the telephone transmitting line L_1 in connection with the cable 70 C and disconnects the telephone receiving line L_2 therefrom, and S_2 puts the telegraph transmitting line TL_1 in connection with the cable and disconnects the telegraph receiving line TL_2 therefrom. The same speech 75 also operates S_3 which is a slow operate relay. This relay puts the telegraph transmitter TT in operation, but due to the fact that it has a greater time lag than the other relays the telegraph transmitter is not made operative until after the line TL_1 has been put in connection with the cable. It will be seen therefore that no loss of telegraph signals due to 80 the change-over can occur.

The other terminal of the cable will be identical with the one shown and will of course 85 be in condition to receive, that is, the corresponding switches will be in the positions shown in the drawing for S_1 , S_2 and S_3 . When speech originates from the other terminal the operation at that end will be the 90 same as described for the terminal illustrated.

In cable circuits having long transmission times, means may be provided to prevent the switches at both terminals being simultaneously operated to the transmitting positions. 95 These means may result in a long time delay between the application of the speech to the amplifier detector (AD_2) and its application to the cable. During this time delay a pulse of tone or other signal may be trans- 100

mitted over the cable, to disable the switch-gear at the distant end and insure a free path for the following transmission. The operating time of the switch S_3 is then made sufficiently long to cover the period thus required for insuring the proper operation of the switches controlling the direction of transmission over the cable circuit.

While only one method of carrying out the invention is here described it will be apparent to those skilled in the art to make numerous modifications and to apply the invention to other systems of voice operated control of telegraph and it must be understood that the scope of the invention is defined in the appended claims.

What is claimed is:

1. A system for transmitting telephone and telegraph signals over a two-way signal transmission medium comprising at a terminal thereof a telephone transmitting circuit, a telegraph transmitting circuit normally disconnected from said medium and including a normally disabled telegraph transmitter, switching means responsive to initiation of telephone signals in said telephone transmitting circuit for connecting said telegraph transmitting circuit to said medium, and switching means also responsive to said telephone signals for conditioning said telegraph transmitter for operation subsequent to the connection of said telegraph transmitting circuit to said medium.

2. A system for transmitting telephone and telegraph signals over a two-way transmission path comprising at a terminal thereof a telephone receiving circuit and a telegraph receiving circuit normally connected to said path so as to receive telephone and telegraph signals, respectively, therefrom, a telephone transmitting circuit and a telegraph transmitting circuit normally disconnected from said path, said telegraph transmitting circuit including a normally disabled telegraph transmitter, switching means responsive to telephone signals initiated in said telephone transmitting circuit for disconnecting said telephone receiving circuit and said telegraph receiving circuit from said path, and for connecting said telephone transmitting circuit and said telegraph transmitting circuit thereto, and slow operate switching means also responsive to the telephone signals initiated in said telephone transmitting circuit for conditioning said telegraph transmitter for operation.

3. A cable system for transmitting speech and telegraph signals over a cable comprising at a terminal thereof telephone and telegraph transmitting branches normally disconnected from the cable, a normally disabled telegraph transmitter in said telegraph branch, switching means responsive to the initiation of telephone signals in said telephone branch for connecting said telephone

and telegraph branches to said cable, and other switching means also responsive to the telephone signals in said telephone branch to condition said telegraph transmitter for operation, said other switching means having a time lag in operation with respect to the first mentioned switching means.

In witness whereof, I hereunto subscribe my name, this 19th day of October, 1931.
